UPHOLSTERED CHAIR

Theodore A. Cowen, Jr., Belvidere, Ill., assignor to Belvedere Products Inc., Belvidere, Ill., a corporation of Illinois

Filed Jan. 15, 1965, Ser. No. 83,460

Term of patent 14 years

(Cl. D15—1)

Fig. 1.

Fig. 2.

Fig. 3.

Fig. 4.

FIG. 2 is a side elevational view of the same;

FIG. 3 is a front elevational view of the same;

FIG. 4 is a rear elevational view of the same.

The dominant features of my design reside in the portions shown in full lines.

I claim:

The ornamental design for an upholstered chair, substantially as shown and described.
